FACE-UP DELIVERY DEVICE FOR A
PRINTING PRESS

Leopold A. Bakke, Chicago, Ill.

Application April 6, 1938, Serial No. 200,531

5 Claims. (Cl. 271—71)

This invention relates to an attachment for a printing press, and more particularly to mechanism for grasping the front end of a sheet after a printing operation and causing the sheet to be inverted before it is released from the machine so as to avoid damage or smearing to the printed face.

The device is of particular utility in connection with high grade printing work such as the making of decalcomania transfers and in colored printing where a sheet may be subjected to several printing operations in different machines.

The invention has been illustrated as applied to a commercial flat bed press but it will be understood that it is applicable to presses of other types such as rotary presses and the like.

In practicing the invention it has been found desirable to have the gripper-jaws, which grip the front end of the sheet, move in a curved path which will keep the front end portion of the sheet in smooth condition without applying tension to an extent that would cause slippage between the sheet and the delivery cylinder.

The invention is illustrated in a preferred embodiment in the accompanying drawings, in which:

Figure 1 is a broken side elevational view of the device mounted on the frame of a flat bed press; Fig. 2 is an enlarged fragmentary elevational view showing how the gripper-jaws engage the front edge of a sheet on the delivery cylinder of the press, taken as indicated at line 2 of Fig. 4; Fig. 3 is a fragmentary end elevational view of the device showing the jaws gripping the front edge of the sheet and holding it in elevated position; and Fig. 4 is a transverse sectional view, taken as indicated at line 4 of Fig. 1.

In the embodiment illustrated, A designates the main frame of a printing press having a reciprocating flat bed A', an impression cylinder A², and a delivery cylinder A³; B, endless conveyor belts for receiving the printed sheets; and C, a face-up delivery device which is driven by the printing press in timed relation thereto.

As printing presses of the type illustrated are well-known in the art, it is not necessary to describe that portion of the machine in detail, but as is well understood, the bed A' reciprocates beneath the impression roll A² through the action of a gear 5 which engages a fixed rack 6 and a moving rack 7. Power is applied from a drive shaft 8 which is geared to a crank shaft 9 provided with a fixed crank 10 which forces the gear 5 back and forth by means of a pitman 11.

The impression cylinder A² has a segmental

gear 12 which is adapted to be driven from a rack 13 provided on the reciprocating bed A'. The gear 12 has a cut-out portion so that the cylinder does not move while the rack 13 makes the return movement to the right, as viewed in Fig. 1. Mechanism (not shown) is provided for turning the impression cylinder A², at the beginning of the forward stroke, sufficiently for the gear 12 to engage the rack 13 and be rotated clockwise to print the next sheet. Thus, it will be understood that the impression cylinder turns in but one direction, and its movement is intermittent.

The delivery cylinder A³ is geared to the cylinder A² so as to make two revolutions for each revolution of the impression cylinder. The delivery cylinder A³ is covered with a surface 14 which is usually kept moist so that contact with the freshly printed face of a printed sheet 15 will not cause injury to the sheet.

The conveyors B are usually in the form of endless narrow belts which fit into grooves on the delivery roll A³ and are reefed about a sheave 16 provided at some convenient delivery place.

The sheet 15, which is to be printed, may be introduced over the top of the machine 17 and has its front edge portion engaged by a gripper 18, provided on the impression cylinder A², and be carried around and impressed against the bed A'. As the front end of the strip reaches the delivery cylinder A³, the gripper 18 is automatically released and the end of the strip engaged by a gripper 19 provided on the delivery cylinder. The latter gripper brings the sheet around the delivery roll to a position where its front end may be engaged by the mechanism C which will now be described in detail. The rotation of the cylinders A² and A³ is stopped at this point while the bed A' is making its return stroke.

The face-up delivery mechanism has a pair of arcuate guide-ways 20 provided on opposite sides of the main frame of the machine. A cross-head or slide-block 21 is confined in a slot thus formed. The upper ends of the guide-ways are connected by a cross-bar 22 and each of the cross-heads is provided with suitable anti-friction rollers (not shown) to facilitate movement. It may be noted that a small presser roller 23 is journaled on the frame A and presses the sheet 15 lightly against the delivery cylinder A³. The point of contact 24 is used as the focus point for the arc of curvature of the ways 20.

The cross-heads 21 are connected together for parallel movement by a fixed cross-bar 25 upon which a series of gripper-jaws 26 are adjustably fixed. A pivot shaft 27 is journaled in the cross-

heads, below the fixed shaft 25, and is provided with a series of gripper-jaws 28. A rock member 29 is fixed to the shaft 27 and serves to move the gripper-jaws 28 to open and closed position. The shaft is also provided with a downwardly extending arm 30 to which is secured one end of a compression spring 31 whose upper end is secured to the cross-head, as indicated at 32, on a center so that the spring will yieldingly urge the gripper-jaws to either open or closed position. A trigger member 33 is pivotally mounted on the frame, as indicated at 34, and has its right end, as viewed in Figs. 1 and 3, urged downwardly against a fixed stud 35 by a tension spring 36. As will be readily understood, when the cross-head 21 is raised, the trigger member 33 will permit an arm of the rock member 29 to pass, by overcoming the tension in the spring 36. On the downward stroke, however, the trigger member will positively engage the arm 29 and continued downward movement of the cross-head will cause the lower gripping-jaws 28 to be flipped to open position. While in this open position the timing of the device with respect to the printing machine will bring the lower open jaw under the front edge of the sheet 15 which will then be automatically released by the grippers 19, and as downward travel of the cross-head continues, the other end of the rock member 29 will engage the fixed stop 37 on the frame and this will cause the jaws 28 to be flipped back to closed position so as to grip the front edge of the sheet 15. While the cylinders A² and A³ remain stationary, the cross-head 21 will move upwardly to the position shown in Fig. 3. When rotation of the cylinder A³ is resumed, the sheet will be doubled back under the device C, starting as indicated by the dotted lines in Fig. 3, and continued movement will cause the printed sheet to be completely inverted and the unprinted face will be brought into contact with the conveyors B. The cross-heads are then lowered automatically and the jaws opened to free the printed sheet and permit it to be conveyed away with its freshly printed face-up.

In order to drive the face-up delivery mechanism in proper timed relation to the printing mechanism, the device is driven from a cam 38 provided on the crank shaft 9, described above. A rock member 39 is pivotally mounted on the frame, as indicated at 40, and has a roller 41 which rides on the cam 38. The opposite end of the rock member is pivotally linked, as indicated at 42, to a pitman 43 which makes an adjustable pivotal connection, as indicated at 44, with a crank 45 provided on a gear shaft 46. The shaft 46 is geared to a rock-shaft 47 extending across the machine and having at each end crank arms 48, whose ends are linked to the cross-heads 21 by means of pitmans 49. Thus, it will be understood that when the shaft 9 is rotated to

operate the reciprocating bed, the cam 39 will serve to raise and lower the cross-heads 21 and the gripping-jaws carried thereby.

The foregoing detailed description has been given for clearness of understanding only, and no unnecessary limitations should be understood therefrom, but the appended claims should be construed as broadly as permissible, in view of the prior art.

I claim:

1. In a sheet printing machine having a delivery roll over which a sheet is fed with the printed face in contact with said roll; endless conveyor belts passing around said roll beneath the sheet; and means for lifting the front edge of said sheet away from the roll while the remainder of the sheet is fed out and inverted so that the unprinted face of the sheet is brought into contact with the conveyor belts.

2. In combination: a printing press having a reciprocating flat bed, an impression cylinder arranged to be driven in one direction by said bed and having a gripper to engage the front end of a sheet and feed it through impression receiving position, a delivery cylinder having a gripper to engage the same end of said sheet when released by the first gripper, and endless conveyor belts passing around said delivery cylinder; and a face-up delivery device comprising a set of gripper jaws adapted to engage the front end of the sheet when released by the second-mentioned gripper, means for lifting said jaws away from the delivery roll before the rear portion sheet is being fed out so that when feeding is resumed the sheet will be curled back, and inverted, and means for opening said gripper-jaws when the sheet rests on said conveyors.

3. A device as specified in claim 2, in which a presser roller is provided to press the sheet lightly against the delivery cylinder, and the jaws are moved by the lifting means in an arc described about the point of contact between the presser roller and delivery cylinder.

4. A device as specified in claim 2, in which gear and cam means is provided for driving the delivery cylinder and face-up delivery device in timed relation so that the jaws are moved upwardly away from the delivery roll while rotation of the delivery roll is stopped.

5. A device as specified in claim 2, in which gear and cam means is provided for driving the delivery cylinder and face-up delivery device in timed relation so that the jaws are moved upwardly away from the delivery roll while rotation of the deliver roll is stopped, and guide means is provided to direct the movement of the jaws in a curved path which will keep the front end portion of the sheet smooth without sliding any of the printed sheet against the face of the delivery roll.

LEOPOLD A. BAKKE.
